ATTORNEY

UNITED STATES PATENT OFFICE.

WILLIAM SPARKS, OF JACKSON, MICHIGAN, ASSIGNOR TO SPARKS-WITHINGTON COMPANY, OF JACKSON, MICHIGAN, A CORPORATION OF OHIO.

HORN.

1,336,594.

Specification of Letters Patent. Patented Apr. 13, 1920.

Application filed December 4, 1918. Serial No. 265,260.

To all whom it may concern:

Be it known that I, WILLIAM SPARKS, a citizen of the United States of America, and resident of Jackson, in the county of Jackson, in the State of Michigan, have invented new and useful Improvements in Horns, of which the following, taken in connection with the accompanying drawings, is a full, clear, and exact description.

10 This invention relates to certain improvements in sound producing devices commonly known as "horns," involving the use of a diaphragm and means for vibrating it together with a sound amplifier and suitable 15 housings for the diaphragm and its actuating means secured together end to end to form a unitary portable structure, and while it is specifically designed for use as an audible signal in trench warfare and other 20 field or naval operations, it is evident that it may be used in other relations where a device of this character might be of service.

It is evident that when a device of this character is used for the specific purpose 25 referred to it must be light, compact and easily portable and at the same time must be simple in construction, durable and reliable in action and easily adjustable to compensate for wear, and the main object is to embody 30 these qualities in an instrument of this character so as to produce the desired tone quality with a minimum number of parts and adjustments.

One of the specific objects is to provide 35 means whereby the diaphragm actuator may be easily and quickly adjusted from the exterior of its housing to compensate for wear or to vary the tone without displacing any of the assembled parts of the 40 device or reducing its efficiency.

Other objects and uses relating to specific parts of the horn will be brought out in the following description.

In the drawings:—

45 Figure —1— is a side elevation of a trench horn embodying the various features of my invention. The portion of the supporting base being shown in section.

Fig. —2— is an enlarged longitudinal sectional view of a portion of the same horn taken on line 2—2, Fig. —1—.

Fig. —3— is an enlarged longitudinal

sectional view of a portion of the horn taken in a plane at right angles to that shown in Fig. —2—.

55

As illustrated, this horn comprises a diaphragm-case —1—, a rotor case —2— secured to one end of the diaphragm-case —1— and a sound-amplifier secured to the opposite end of the diaphragm-case, all of 60 which parts are preferably circular in cross section and secured together end to end in co-axial relation to form a unitary structure or housing adapted to be mounted upon a suitable supporting base —4— through 65 the medium of a bracket or standard —5—, having one end secured to the case —1— by screws —6— or equivalent fastening devices and its other end adjustably mounted in the base —4— and held in place by a set-screw 70 —7—.

The diaphragm-case —1— preferably consists of a ring-section —8— and a cap-section —9— removably secured around its marginal edge to the corresponding margin 75 of the ring —8— by screws —10— or equivalent fastening devices, the cap-section —9— being provided with a circular tubular boss —11— for receiving and supporting the adjacent end of the sound-amplifier —3—.

A circular diaphragm —12— extends across the openings in the ring —8— and cap-section —9— and has its marginal edge inclosed in a rubber or equivalent packing 85 —13— and secured between the adjacent marginal edges of said ring and cap-section by the screws —10— as shown more clearly in Fig. —2—, the packing-rings or gaskets —13— serving to yieldingly support the 90 marginal edge of the diaphragm separate from the metal parts —8— and —9— thereby reducing the liability of crystallization of the diaphragm at its points of securement as might result from continued vibration of the diaphragm if the marginal edges thereof were rigidly held by and in direct contact with the metal parts —8— and —9—.

A suitable anvil or contact-member 100 —14— is riveted or otherwise secured to the central portion of the diaphragm —12— and is provided with a V-shaped end projecting into the adjacent end of the rotor-

case —2— for engagement by a rotary beater constituting a part of the diaphragm actuating means presently described.

The case —2— is circular in cross section 5 and serves to receive and support the diaphragm actuating mechanism comprising in this instance a toothed-wheel or rotor —15— centrally mounted upon a rotary shaft —16— which extends diametrically 10 of the diaphragm a distance from the V-shaped end of the anvil —14— approximately equal to the radius of the toothed-wheel —15—, measured from its pitch-circle, and has its ends journaled in suitable 15 bearings —17— and —18— in diametrically opposite sides of the case —2—.

The wheel —15— revolves in a plane substantially coincident with the axis of the diaphragm and is provided with a V-shaped 20 peripheral-tooth —19— for engagement with the corresponding V-shaped end of the anvil —14— so as to cause the vibration of the diaphragm as the wheel —15— is rotated in one or the reverse direction.

25 It is now clear that the toothed-wheel —15— is located substantially midway between opposite sides of the casing —2— and substantially normal to the plane of the diaphragm so that the shaft —16— is parallel, or approximately so, with said diaphragm, although suitable provision is made 30 for slightly varying this normal relation between the diaphragm and its actuator to compensate for wear and also to vary the 35 tone when required.

For this purpose the ends of the shaft —16— are conical while the bearings —17— and —18— are preferably made separate from the shell —2— and consists of adjusting screws having their inner ends provided 40 with conical sockets of greater angles than the conical ends of the shaft so as to allow one end of the shaft to be adjusted readily toward and from the diaphragm without 45 disturbing the bearing for the other end of the shaft while at the same time both bearings may be adjusted axially to prevent lost motion of the shaft —16— therein.

The bearing —17— is screwed into the 50 adjacent side of the shell and is held in place by a lock-nut —17'—. The opposite bearing —18— is mounted upon a radially movable sliding support —21— and extends outwardly through an elongated slot —20— 55 in the adjacent side of the case —2— and together with the sliding support —21— may be locked and held in its adjusted position by a lock-nut —18'—.

The sliding support —21— is movable 60 lengthwise of and against the inner face of the adjacent side of the case —2— and may be adjusted longitudinally by means of an adjusting screw —22— which is screwed in the outer end wall of the case —2— and is 65 held in its adjusted position by a lock-nut

—22'—, the inner end of the screw —22— being provided with an annular groove for receiving a radially projecting forked end —21'— of the sliding support —21— thus permitting the bar —21— to be adjusted in 70 reverse directions to effect a corresponding adjustment of the adjacent end of the shaft —16— and toothed-wheel —15— for the purpose of taking up wear between the toothed-wheel and anvil of the diaphragm, 75 and varying the tone when required.

A relatively small pinion —23— is secured to the shaft —16— between the bearing —17— and toothed-wheel —15— and preferably nearer the bearing —17— and 80 meshes with a relatively large gear —24— which is secured to one end of a crank-shaft —25— within the case —2—.

This crank-shaft —25— is journaled in a bushing —26— in the adjacent side of the 85 case —2— and is provided with a handle —25'— by which it may be rotated to transmit motion to the diaphragm-actuator or wheel —15— through the medium of the gears —23— and —24—.

90 The base —4— may be secured to or may rest loosely upon any available support within a trench or in any other desired locality and the horn then raised or lowered to the desired height by means of the standard, and locked in its adjusted position by the set-screw —7— ready for operation by 95 simply rotating the crank-shaft —25—.

If the contacting portions of the wheel —15— and anvil —14— should become 100 impaired by wear or if a louder or softer tone should be required the screw —22— may be readily adjusted from the exterior of the case by means of a screw-driver or similar instrument to effect the desired adjustment 105 of the toothed-wheel —15— closer to or farther from the anvil through the medium of the bar —21— and bearing —18— thereon.

110 What I claim is:

A signaling device comprising a diaphragm, a casing extending rearwardly therefrom, a bearing member extending through one side of the casing and adjustable therethrough in a direction substantially parallel with the diaphragm and means for locking the said bearing member in any of its predetermined adjusted positions, said bearing member having a substantially conical bearing seat, said casing formed with an opening through its wall at a point substantially opposite the said bearing member, a sliding bar mounted within the casing and having an opening registering with said opening through the casing and of less length than the opening through the casing, a second bearing member extending through an opening in the casing and adapted for longitudinal movement therein, said second bearing extending 120 125 130

through the opening in said sliding bar and substantially fitting the said opening and secured to the bar and formed with a conical bearing seat, means for locking the second named bearing in any longitudinal adjusted position with reference to the casing, means secured to the sliding bar and extending through the casing for adjusting said bar and thereby said second named bearing, 10 a shaft having its opposite ends tapered and

mounted in respective conical seats in said bearing members, a diaphragm actuator mounted on the said shaft and means for driving the shaft.

In witness whereof I have hereunto set 15 my hand this 4th day of November, 1918.

WILLIAM SPARKS.

Witnesses:

LILLIAN WUNDERLICH,
W. J. CORBETT.
